DOOR CONSTRUCTION

Howard H. Turner, Lawndale, Calif.

Application December 20, 1943, Serial No. 514,881

12 Claims. (Cl. 160—27)

My invention relates to a door construction, and more particularly to a combination window and screen for a door.

An important object of the invention is to provide means for connecting, end to end, a screen and a window, in a door construction, whereby they are moved simultaneously. That is, as the screen is moved out of the door opening, the window proportionately moves into the door opening, and vice versa.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a perspective view, partly broken away, showing an embodiment of the foregoing objects, showing the window in a lowered position.

Fig. 2 is an enlarged, transverse section of said embodiment, but indicating the window in a raised position.

Fig. 3 is a perspective view of a handle comprised in the invention.

Fig. 4 is a broken, perspective view of screen clamping means.

Fig. 5 is a perspective view of said embodiment, with still other parts broken away.

Fig. 6 is an enlarged section taken on the line 6—6 of Fig. 5.

Fig. 7 is a perspective sectional view, showing a detail hereinafter more fully described.

Fig. 8 is an enlarged broken section taken along the line 8—8 of Fig. 5.

Fig. 9 is a perspective view of a roller employed to roll up the screen.

Fig. 10 is an inside, perspective view of a roller cover plate utilized in said embodiment.

Fig. 11 is perspective view of a locking lever comprised in the invention.

Referring more in detail to the drawings, the reference numbers 12 and 13 designate the top and bottom stiles of a door construction. Side stiles are shown at 14 and 15, and the center mul-
lion at 16. Panels 17 and 18 are arranged between

the center and bottom stiles and between the side stiles. The panels 17 and 18 are disposed with a space 19 between them, in which space the window 20 may be lowered. Molding 21 is tacked around the edge of the panels 17 and 18.

At the bottom of the space 19 between the panels are beveled blocks 22 and 23 that direct any moisture that enters the space 19, to an inclined vent 24.

10 A recess 25 in the top stile 12 houses a roller 26, upon which the screen 27 is wound. The screen may be a plastic, perforate screen, a copper, woven screen, or any other suitable perforate material. The lower edge of the screen 27 is fastened to the window 20 by means hereinafter described.

The roller 26 has a slot 28 in which the upper edge of the screen 27 is inserted. Then a strip 29 is driven in the slot 28, wedging the edge of the screen therein. An end of the roller 26 is enclosed in a cap 30. This cap rotates in a sleeve 31. The cap and sleeve are preferably of wear-resisting material; e. g., metal.

The capped end of the roller 26 is apertured 25 at 32 to receive the end of wire 33 which coils about the roller. The opposite end of the wire is connected with a helical spring 34 that is anchored by a hook 35. The wire 33 and spring 34 are disposed to move lengthwise in a bore 36 in

30 the stile 14 of the door. The end of the roller 26, opposite to the capped end, turns in a journal 37 in the upper stile 12. A cover plate 38 encloses the recess 25. The plate 38 is screwed in place, as suggested at 39.

35 A control lever 40 is pivoted on a screw 41, to swing between the stile 12 and the cover 38. The lever 40 has a detent 42, which in one position of the lever 40 is opposite a pin 43. The pin 43 has a round head 44. A spring 45 tends to move the

40 head 44 to an engaging position with a plate 46 on a handle 47. When the detent 42 is not in engagement with the pin 43, the plate 46 and the window 20 may be lowered, since the headed pin 43 acts as a spring catch in connection with the

45 flange 48 of the plate 46. However, when the lever 40 is moved to a position in which the detent 42 is opposite the pin 43, movement of the head 44 to the left in Fig. 2 is thereby prevented, thus locking the window 20 in its closed position. It 50 is to be understood that the lever 40 is on the inside of the door, so as to prevent anyone on the outside from lowering the glass and breaking through the screen 27.

Welded back to back with the plate 46 is a 55 channel-shaped member 49, provided with an in-

ward flange 50. A clamping strip 51 for the screen 27 has a portion 52 folded upon itself. In assembling, the screen 27 is placed around the inner surface of the channel 49, and the strip 51 is then forced into the channel until a strip portion 52 engages under the flange 50, thus clamping the lower end of screen 27 in the channel 49.

A U-shaped strip 53 is arranged within the handle 47 to re-enforce same. A gripping strip 54 engages over the top of the window 20, and is in turn engaged by a flange 55 depending from the handle 47. A resilient pad 62 is placed over the upper edge of glass 20 beneath the gripping strip 54.

Moulding 56 extends along the sides of the opening in the door that is automatically closed by the screen or window, or part of each. Felt strips 57 line the inner faces of the moulding 56 while suitable resilient material 58 lines the upper inner edges of the center stile 16. It will be noticed in Fig. 5 that the center stile 16 is cut to provide a slot 59 through which the window 20 may be lowered. On the under side of stile 16, an angle bracket 60 may be employed to prevent the panel 18 from being pushed into the path of the window 20. This construction is shown enlarged in Fig. 7. The cover plate 38 has a notch 61 on the inner side in which the lever 40 operates.

In the use of my invention, either the screen or the window, or portions of both, may be exposed at the opening through the door. The lever 40 may be moved to lock the window in the closed position. By moving the lever 40 out of the path of the pin 43, the window 20 may be lowered.

As the window is lowered, the screen 27 is progressively unwound and the wire 33 is wound upon the roller 26, against the action of the spring 34. Thus, when the window is again raised, the tension placed in the spring 34 tends to wind up the screen upon the roller 26. The cap 30 and sleeve 31 are at the end of the roller 26 that receives the most wear and strain, since the wire 33 is connected to the roller 26 at such end. It is to be understood that the spring 34 is not strong enough to raise the window alone, but merely to rotate the roller 26 when the window is manually raised.

Removal of the cover plate 38 provides access to the roller in case repair or replacement is desired.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In a door construction having an opening therethru and a slotted center mullion, the combination of a screen, a window connected edge-to-edge with the screen, the window being mounted on the door to slide thru the slotted mullion to and from positions at the opening thereof, a spring roller journaled on the door and connected to, roll up the screen as the window is moved into the opening and to unroll the screen as the window is moved from the opening, and means to lock the window in the closed position at the opening.

2. In a door construction having an opening

therethru, the combination of a screen, a window connected edge-to-edge with the screen, the screen and window being mounted on the door to slide to and from positions at the opening, a roller journaled on the door and connected to roll up the screen as the window is moved into the opening and to unroll the screen as the window is moved from the opening, the window carrying an abutment, a latch mounted on the door, resilient means urging said latch into the path of the window abutment, the latch having a curved face that is engaged by the abutment, and movable lever locking means adapted to lock the latch in a window-locking position and to be moved to a window-releasing position.

3. In a door construction having an opening therethru, the combination of a screen, a window, the screen and window being mounted on the door means connecting the screen and window in edge-abutting positions comprising a resilient channel shaped member on the window having an abutment and a clamping member clamping the screen in the channel and having abutment means to engage the abutment of the channel member to prevent accidental displacement of one member from the other, the resilience of the channel member resiliently opposing removal of the clamping member and the screen from the channel, and a roller journaled on the door and connected to roll up the screen as the window is moved into the opening and to unroll the screen as the window is moved from the opening.

4. In a door construction having an opening therethru, the combination of a screen, a window connected edge-to-edge with the screen, the door having spaced panels adjacent the opening and the window being mounted on the door to be moved from between the panels to a position closing the opening and return, an inclined surface at the bottom of the space between the panels, the door having a vent extending from a lower portion of the inclined surface to the bottom of the door, and a roller journaled on the door and connected to roll up the screen as the window is moved into the opening and to unroll the screen as the window is moved from the opening.

5. In a door construction having an opening therethrough, the combination of a screen and a window mounted on the door, means connecting the screen and window in edge to edge relation, comprising a channel member, means cooperating with said channel member to clamp said screen in said channel member, and a roller on the door to roll up the screen as the window is moved into the opening and to unroll the screen as the window is moved from the opening.

6. In a door construction having an opening therethrough, the combination of a screen and a window mounted on the door, means connecting the screen and window in edge abutting positions comprising a resilient channel member associated with the window and provided with an abutment, means cooperating with said channel member to clamp said screen in said channel member, said means having an abutment which cooperates with said first-named abutment to prevent dissociation of said clamping means from said channel means, and a roller on the door to roll up the screen as the window is moved into the opening and to unroll the screen as the window is moved from the opening.

7. In a door construction having an opening therethrough, the combination of a screen, a

window mounted on the door connected edge to edge with the screen, a roller on the door to roll up the screen as the window is moved into the opening and to unroll the screen as the window is moved from the opening, an abutment on the window, a latch mounted on the door and disposed in the path of said abutment, and means on the door to lock the latch in a window locking position or to be moved to a window releasing position.

8. In a door construction having an opening therethrough, the combination of a screen, a window, a channel member secured to said window, a member cooperating with said channel member to clamp said screen in edge to edge relation with said window, the screen and window being mounted on the door to slide to and from positions at the opening, an abutment on said window, a latch mounted on said door and disposed in the path of said abutment, and a lever on the door to control the locking or releasing position of the latch.

9. In a door construction having an opening therethrough, the combination of a screen and a window mounted on the door, a channel member secured to said window, means for clamping said screen in said channel member, and a roller on the door to roll up and unroll said screen as the window is moved respectively into and from the door opening.

10. In a door construction having an opening therethrough, the combination of a screen and a window mounted on the door, mutually inter-

locking means for connecting the screen and window in end to end relation, one of said means having an abutment, a latch on said door disposed in the path of said abutment, and means to lock said latch in window locking or to be moved to window releasing position.

11. In a door construction having an opening therethrough, the combination of a screen and a window mounted on the door, mutually co-
10 operating means associated with the window for clamping the screen in end to end relation with the window, at least one of said means being resilient, the door having spaced panels adjacent the opening and the window being slidably mounted therebetween to be moved to closing or opening positions, said door having a vent in the bottom thereof, and an inclined surface to deflect moisture to said vent.

12. In a door construction having an opening therethrough, the combination of a screen and a window mounted on the door, means connecting the screen and window in edge abutting position, comprising a resilient member attached to said window and having an abutment, and a
20 member cooperating with said resilient member to clamp said screen under the abutment of said resilient member, said abutment locking said cooperating member against dissociation from said resilient member, a latch on said door, and means to hold said latch in window locking and to be moved to window releasing position.

HOWARD H. TURNER.
